REFLEX OSCILLATOR TUBE

Rowland W. Haegele, San Mateo, Calif., assignor to Eitel-McCullough, Inc., San Bruno, Calif., a corporation of California

Application January 5, 1953, Serial No. 329,630

6 Claims. (Cl. 315—5.22)

My invention relates to an improved electron discharge device of the reflux klystron type.

It is among the objects of my invention to provide an improved envelope structure for a tube of the character described, designed for compactness and maximum ruggedness.

A further object is to provide improvements in the cavity resonator structure of such a tube.

Still another object is to provide an improved tuner construction.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawing, the single figure is an axial sectional view of a tube embodying the improvements of my invention.

In greater detail, my tube comprises a generally cylindrical evacuated metal envelope having upper and lower tubular end sections 2 and 3. Between these sections is interposed a circular cavity resonator comprising an upper cup-shaped metal wall portion 4 and a lower disk-shaped metal wall portion 6. The lower wall portion of the resonator has an upturned lip 7 and the cylindrical side of the upper wall portion has a cooperating upturned lip 8 with an edge registering with that of the lip 7. These registering edges are metallically bonded by a braze 9 along the periphery of the resonator.

Cup-shaped wall portion 4 of the resonator encircles the upper envelope section 2 with a top flange 5 secured at the braze 11 to the cylindrical surface of such section. The inner end of envelope section 2 thus projects into the resonator and is provided with a central opening 12 which serves as one of the resonator apertures. Disk-shaped wall portion 6 of the resonator is brazed at 13 to the lipped inner end of the lower envelope section 3 and has a reentrant projection 14 having an aperture 16 adjacent to and aligned with aperture 12.

This structural arrangement provides a simple envelope with coaxial end sections having a circular cavity resonator therebetween, all of which is made up of stamped metal parts which are easy to assemble and braze together. The structure is also compact and has the ruggedness which is desirable in a tube of this kind.

A cathode 17 is supported in the lower envelope section 3 adjacent one side of the resonator and a repeller electrode 18 is supported in the upper envelope section 2 adjacent the other side of the resonator, the cathode and repeller being axially aligned with the resonator apertures 12 and 16. Cathode 17 is preferably of the oxide coated type, shaped as a flat button, and is mounted on a sleeve 19 connected to the inner end of a tubular terminal 21 which forms part of the cathode stem.

Terminal 21 is in turn supported by a metal U-shaped

2

sealing ring 22 fitted in the enlarged end of envelope section 3, a vitreous body 23 such as glass being sealed between the terminal and the inner flange of the supporting ring. The lower edge of ring 22 registers with the edge of the envelope section, and these registering edges are metallically united by a braze 24.

A heater 26 positioned within the cathode assembly is connected at one end to the cathode terminal and at the other end to a central terminal prong 27. The latter is supported by a sleeve 28 brazed to and projecting downwardly within the tubular terminal, a vitreous bead 29 being sealed between the prong and sleeve. The electron gun assembly is completed by a focusing sleeve 31 extending upwardly from terminal 21 about the cathode sleeve and having a focusing portion projecting beyond the cathode.

The supporting stem for the repeller electrode 18 is mounted in the upper end of the envelope in a manner similar to the cathode stem, namely, by means of a sealing ring 32 secured by a braze 33 and connected to a tubular terminal 34 by a vitreous body 36. The disk-like repeller electrode is supported on the inner end of terminal 34 by a perforated bracket 36. This stem structure also carries a metal exhaust tubulation 47 which is pinched off at tip 38 after exhaust.

A resonator grid 39 is preferably mounted on the inner end of envelope section 2 across the upper aperture 12, and a similar grid 41 is mounted on the reentrant projection 14 across the lower aperture 16. An accelerator grid 42 is also preferably arranged below the resonator, this grid being mounted on the resonator wall below the projection 14.

Energy is preferably coupled out of the resonator by a coaxial line 43 having an inner conductor 44 terminating in a coupling loop 46. This output line is located externally of the envelope and enters the resonator through the disk-shaped wall portion 6, the line being supported adjacent the outer end by passing through a mounting flange 47 secured to lower envelope section 3. Inner conductor 44 is spaced from the outer conductor by insulating tube 48, and a vacuum-tight seal is provided by a glass bead 49.

A tuning structure is provided for changing the spacing between the resonator grids 39 and 41 to adjust the gap between the grids and hence the operating frequency of the tube. This spacing need not be changed greatly to give a reasonable tuning range. I achieve this in a simple way by fastening a first flange 51 on the side of the upper wall portion 4 of the resonator, and a second flange 52 on the upper section 2 of the envelope. The tuning is effected by screw means extending between the flanges, such as by studs 53 fastened to the lower flange and having nuts 54 engaging the upper flange so that the flanges may be moved relative to each other by adjusting the nuts. The top flange 5 of the upper wall portion has sufficient flexibility under the pressure exerted by the adjusting screws to permit the slight changes necessary in the spacing between the grids. For fine tuning, one of the screw means is preferably a differentially threaded screw 56 so final setting of the frequency can be achieved with a screwdriver.

In other respects the cavity structure is quite rigid, so that once the frequency is set, it does not change. As shown, the lower disk-shaped wall portion 6 is preferably formed with an arcuate depression or groove to provide a reinforcing rib to further enhance the rigidity of the structure. The adjusting screws are preferably made of the same kind of metal as that used in the tube envelope construction so that the thermal expansion properties are consistent.

I claim:

1. A reflex oscillator tube comprising a generally cylindrical envelope having upper and lower tubular metal end sections, a cathode in the envelope supported by the lower end section, a repeller electrode in the envelope supported by the upper end section, a cavity resonator interposed between the end sections and comprising upper and lower wall portions of metal having edges registering along the periphery of the resonator, said upper portion being cup-shaped with a generally radial top flange secured to the external cylindrical surface of the upper envelope section intermediate the ends of the latter, said lower portion being disk-shaped and secured to the upper end of the lower envelope section, said top flange being flexible to permit tuning of the tube, and a metallic bond uniting said registering edges along the periphery of the resonator.

2. A reflex oscillator tube comprising a generally cylindrical envelope having upper and lower tubular metal end sections, a cathode in the envelope supported by the lower end section, a repeller electrode in the envelope supported by the upper end section, a cavity resonator interposed between the end sections and comprising upper and lower wall portions of metal having edges registering along the periphery of the resonator, said upper portion being cup-shaped with a top flange secured to the external cylindrical surface of the upper envelope section intermediate the ends of the latter, said lower portion being disk-shaped and secured to the upper end of the lower envelope section, said top flange being flexible to permit tuning of the tube, a metallic bond uniting said registering edges along the periphery of the resonator, the inner end of the upper envelope section projecting into the resonator and having a central aperture, and a reentrant projection on the disk-shaped wall portion having an aperture aligned with said first named aperture.

3. A reflex oscillator tube comprising a generally cylindrical envelope having upper and lower tubular metal end sections, a cathode in the envelope supported by the lower end section, a repeller electrode in the envelope supported by the upper end section, a cavity resonator interposed between the end sections and comprising upper and lower wall portions of metal having edges registering along the periphery of the resonator, said upper portion being cup-shaped with a top flange secured to the cylindrical surface of the upper envelope section intermediate the ends of the latter, said lower portion being disk-shaped and secured to the inner end of the lower envelope section, said top flange being flexible to permit tuning of the tube, a metallic bond uniting said registering edges along the periphery of the resonator, the upper end of the upper envelope section projecting into the resonator and having a central aperture, a reentrant projection on the disk-shaped wall portion having an aperture aligned with said first named aperture, and grids mounted across said apertures.

4. A reflex oscillator tube comprising a generally cylindrical envelope having upper and lower tubular metal end sections, a cathode in the envelope supported by the lower end section, a repeller electrode in the envelope supported by the upper end section, a cavity resonator interposed between the end sections and comprising upper and lower wall portions of metal having edges registering along the periphery of the resonator, said upper portion being cup-shaped with a generally radial top flange secured to the cylindrical surface of the upper envelope

section secured intermediate the ends of the latter, said lower portion being disk-shaped and secured to the upper end of the lower envelope section, a metallic bond uniting said registering edges along the periphery of the resonator, a tuning structure for the tube comprising a first member fastened to the resonator and a second member secured to the upper envelope section, and means for moving said first and said second members relative to each other, whereby said top flange is flexed by forces applied by said first and said second members to the inner and outer edges of said top flange.

5. A reflex oscillator tube comprising a generally cylindrical envelope having upper and lower tubular metal end sections, a cathode in the envelope supported by the lower end section, a repeller electrode in the envelope supported by the upper end section, a cavity resonator interposed between the end sections and comprising upper and lower wall portions of metal having edges registering along the periphery of the resonator, a metallic bond uniting said registering edges, said upper portion being cup-shaped with a generally radial top flange secured to the external cylindrical surface of the upper envelope section, said lower portion being disk-shaped and secured to the upper end of the lower envelope section, said lower portion of said resonator and said upper end section of said envelope to effect relative axial displacement between the upper end section of said envelope and the outer edge of said flange by flexure of said generally radial top flange.

6. A reflex oscillator tube comprising a generally cylindrical envelope having upper and lower tubular metal end sections, a cathode in the envelope supported by the lower end section, a repeller electrode in the envelope supported by the upper end section, a cavity resonator interposed between the end sections and comprising upper and lower wall portions of metal having edges registering along the periphery of the upper end section and along the upper end of said lower end section, said upper portion being cup-shaped, said lower portion being disc-shaped, said lower portion of said resonator and said upper end section of said envelope having aligned apertures, resonator grids extending across each of said apertures, and a tuning structure comprising means connected between said resonator and said upper end section of said envelope to effect relative axial displacement of the upper end section with respect to the outer wall of said resonator by flexure of the radial portion of said upper wall portion of said resonator said tuning means further comprising a plurality of screws at least one of which is differentially threaded to provide a fine tuning adjustment.

UNITED STATES PATENT OFFICE
CERTIFICATE OF CORRECTION

Patent No. 2,825,843

March 4, 1958

Rowland W. Haegele

It is hereby certified that error appears in the printed specification of the above numbered patent requiring correction and that the said Letters Patent should read as corrected below.

Column 1, line 16, for "reflux" read -- reflex --; line 59, for "assembly" read -- assemble --; column 3, line 45, for "secured to the" read -- secured to the external --; line 48, for "inner" read -- upper --; line 51, for "upper" read -- inner --.

Signed and sealed this 3rd day of June 1958.
